R. P. COWLES, OF NEW HAVEN, CONNECTICUT, ASSIGNOR TO C. COWLES
& CO., OF SAME PLACE.

Design No. 2,534, dated January 1, 1867.

DESIGN FOR A COACH LAMP.

The Schedule referred to in these Letters Patent and making part of the same.

TO ALL WHOM IT MAY CONCERN:

Be it known that I, R. P. COWLES, of New Haven, in the county of New Haven, and State of Connecticut, have invented a new Design for Coach Lamp; and I do hereby declare the following, when taken in connection with the accompanying drawings and the letters of reference marked thereon, to be a full, clear, and exact description of the same, and which said drawings constitute part of this specification, and represent, in—

Figure 1, a side view.

Figure 2, a front view.

Figures 3 and 5, face view of the lights; and in

Figures 4 and 6, edge views of the same.

This design relates more particularly to the form of the lights, than to other parts of the lamp; and in this peculiar form of the lights and the frame which supports the lights, the design consists.

To enable others to construct my improvement, I will proceed to describe the same as illustrated in the accompanying drawings.

A is the socket, B the body, and C the top, the socket and top being no part of the design, but shown simply to illustrate the adaptation of the design. The lights, D, are alike in form upon as many sides as lights are placed, are octagon in form, as seen in figs. 3 and 4. The frame, E, which supports them, projects from the body of the lamp, swelling from the body towards the lights, as seen in figs. 4 and 6.

What I claim, is the herein-described design for the lights D, and their supporting frames E.

Witnesses:

JOHN E. EARLE,
A. J. TIBBITS.

R. P. COWLES.
